ELECTRICAL CONNECTOR HOUSING

Norman E. Hoffman, Norristown, Pa., assignor to
AMP Incorporated, Harrisburg, Pa.

Filed June 10, 1963, Ser. No. 75,298

Term of patent 14 years

(Cl. D26—1)

Fig. 1

Fig. 2

Fig. 3

FIGURE 1 is a longitudinal plan view of an electrical connector housing, showing my new design;

FIGURE 2 is a longitudinal plan view of the device shown in FIGURE 1, rotated forty-five degrees; and

FIGURE 3 is a top view of the device shown in FIGURE 1.

I claim:

The ornamental design for electrical connector housing as shown.
